DESIGN FOR AN AIRPLANE

Raymond C. Blaylock, Bexley, Ohio

Application November 30, 1942, Serial No. 108,907

Term of patent 7 years

To all whom it may concern:

Be it known that I, Raymond C. Blaylock, a citizen of the United States, residing at Bexley, State of Ohio, have invented a new, original, and ornamental Design for an Airplane, of which the following is a specification, reference being had to the accompanying drawing forming a part thereof.

Fig. 1 is a top plan view of an airplane showing my new design.

Fig. 2 is a front elevational view.

Fig. 3 is a side elevational view.

Fig. 4 is a perspective view thereof.

Fig. 5 is a front elevational view of the airplane on the ground and its wings folded upwardly.

I claim:

The ornamental design for an airplane, as shown.

RAYMOND C. BLAYLOCK.
